(57) **CLAIM**

The ornamental design for an offset handle for a taping knife, as shown and described.

DESCRIPTION

FIG. 1 is a front view of the present taping knife handle; FIG. 2 is a rear view of same;

FIG. 3 is a left side view of the taping knife handle of FIG. 1;

FIG. 4 is a right side view of same;

FIG. 5 is a top view of the taping knife handle of FIG. 1; FIG. 6 is a bottom view of same; and,

FIG. 7 is a top perspective view of the taping knife handle of FIG. 1.

The subject matter depicted in broken lines is not intended to be part of the claimed invention and is shown only for environment purposes.
